CLAIM

The ornamental design for a detent coupled drill bit
chuck, or the like as shown.

DESCRIPTION

FIG. 1 is a front perspective view of a detent coupled
drill bit chuck or the like, showing my new design;
FIG. 2 is a side elevation thereof;
FIG. 3 is a top plan view thereof;
FIG. 4 is a bottom plan view thereof; and
FIG. 5 is a cross-section taken on line 5—5 of FIG. 1.
